UNITED STATES PATENT OFFICE.

JAMES H. BLACKMORE, OF AURORA, ILLINOIS.

SULKY.

SPECIFICATION forming part of Letters Patent No. 239,218, dated March 22, 1881.

Application filed November 22, 1880. (No model.)

To all whom it may concern:

Be it known that I, JAMES H. BLACKMORE, residing at Aurora, in the county of Kane and State of Illinois, and a citizen of the 5 United States, have invented new and useful Improvements in Sulkies, of which the following is a full description, reference being had to the accompanying drawings, in which—

Figure 1 is a perspective view of a sulky 10 constructed according to my invention, the wheels being omitted. Fig. 2 is a longitudinal central section. Fig. 3 is a side elevation of the sulky without wheels. Fig. 4 is a detached view of the foot-boards. Fig. 5 is a 15 view illustrating a modification of the foot-support. Fig. 6 is a detached view, illustrating the form and arrangement of the single-tree.

This invention relates to sulkies or two-wheeled vehicles which have a spring-seat and a platform or foot rest or support to move with the seat and relieve the feet and knees from jarring action in use. Its objects are to facilitate the balancing of the sulky with respect 25 to the weight of the driver, to simplify the construction of the vehicle, to enable the horse to be hitched close to the axle, and to simplify the application of springs to sulkies.

In the drawings, *a* indicates the axle of a 30 sulky; *b*, connecting rod or rods; *c*, the shafts; *d*, seat-arms; *e*, the seat; *f*, thumb-screws; *g*, the bar of the foot-rest; *h*, cross-slats of the foot-rest; *i*, spring; *j*, the whiffle-tree; *k*, the cross-bar; *l*, stirrup; *m*, clip; *n*, brace; *o*, pivot; *p*, eyes or loops.

The wheels, axle, and shafts are made in any of the usual or well-known forms in the ordinary manner.

The seat, which may be single or double, in 40 the form shown, is supported upon the rear ends of the arms *d*, and firmly attached to each of these seat-arms at their forward ends is a strong pivot, *o*, which passes beneath the shaft *c*, upon which they turn, and it is held 45 in place by an eye or loop of metal, *p*, through which it passes, which is secured to the shaft by screws or other suitable fastenings. On the outer end of this pivot a thread is cut, and 50 a nut screwed thereon holds it securely in the eye or loop. I place and arrange two or more of these eyes or loops *p* on the under side of

each shaft, a short distance apart, as shown, and they are preferably cut or formed into a single piece of metal. As the seat-arms are thrown forward or backward upon the shafts 55 the weight of the seat-burden is increased or lessened upon the back of the horse, and thus a proper and desirable poise or balance of the vehicle can be maintained with varying burdens by shifting the pivot in the eyes, which 60 is readily done by removing the nut upon its end; and if the seat parts and the parts of the foot-rest are arranged to turn on the same pivots, which is a preferable arrangement, they are all shifted together. If thrown backward, 65 additional room is obtained for the horse, permitting him to be hooked nearer the axle.

It is apparent that my invention will permit the vehicle to be regulated to suit the lengths or sizes of different horses. When the 70 foot-rest is shifted or arranged backward to make room for the horse, I can still regulate and preserve the poise and balance of the vehicle by moving the shifting or sliding seat *e* upon the arms *d*. These arms *d* have each a 75 mortise or slot cut in them underneath the seat *e*, in each of which a thumb-screw is arranged, having a shoulder against the arm, which can be moved backward and forward, and which can be readily turned into nuts secured beneath the seat-frame, and in this manner the seat is firmly held at any point within the range of the slot.

It is evident that other kinds of shifting devices might be used to secure the seat in 85 position.

The eyes *p* may be of wood or other suitable material, and may be so constructed as to furnish a thin metal plate between the pivot and shaft. They may be given position on the 90 upper surface of the shafts, or on either side, or on the seat-arm, or on the cross-bar, with a relative change in the attachment of the pivot, which may be passed through the shaft or seat-arm, if desired.

I do not confine myself to eyes or loops *p* through which to pass the pivots. Two or more half-eyes or staples may be placed on each shaft, and in some forms of attachment simple holes, spurs, or pins may be used to 100 provide places for different points for attachment and adjustment. It is evident that va-

rious devices may be used for attaching the seat-bars to the cross-bar or shafts.

The seat-arms *d* may be bent or drawn inward at their rear ends, according to the size 5 of the seat desired, and in the form shown they pass over rubber or other suitable springs, *i*, which are supported by the shafts or frame. Suitable springs may be supported upon the seat-arms *d* and be given bearing upon the 10 shafts or other part; or the seat may have other form of spring-support. In some forms of construction the arms *d* may be rigidly or both rigidly and adjustably secured to the shafts.

The cross-slats of the platform or foot-rest, 15 if of wood, are preferably bent or formed so that the grain of the wood runs the full length of them, or nearly so, and they are secured upon the bar *g* by bolts, screws, or other suitable fastenings, which bar is supported upon 20 the springs, seat-arms, cross-bar, or shafts by rods, bolts, or other usual or suitable connections. I prefer that the seat and the foot-rest be so arranged as to maintain the same relative positions to each other, or nearly the same, 25 when in use. In the form shown the support of the cross-slats of the foot-rest is a continuous bar of wood or other suitable material, semi-circular in form at the rear, and bent or curved upward at its forward ends; but it may be in 30 two pieces, and they may be straight bars or deflected at any desired point in their length, and it may be of two or more pieces so rigidly and securely connected as to make practically a single or continuous bar. A continuous bar, 35 or one practically so, greatly strengthens and stiffens the feet-supporting device at its rear end, and there is less liability of racking and of breakage of the parts. By giving the cross pieces or slats *h* a bent or curved form, as 40 shown, I have upon the upper margins of the foot-rest sufficient room and stretch for the legs and feet of the driver, and provide additional space back of the horse, between the feet and legs of the driver, for the action of 45 the animal, and avoid the objection of having too great length in the shafts. If straight cross pieces or slats were used, the horse would necessarily be hooked farther forward in the shafts, which would require to be made relatively longer. Several of these cross-slats are 50 used in the construction of the foot-rest, and they are preferably placed a little distance apart, as shown; but they may be given position close together, and in this form the foot-rest is much stronger than when made of one or more boards having a concavity cut or sawed 55 into the front board.

The foot-rest may be constructed with one or more straight cross-slats and one or more 60 curved or bent cross-slats in combination, the latter being placed at the front end of the foot-rest with their concave sides toward the front of the vehicle.

The platform or foot-rest, formed and described as above, may be dispensed with in 65 such vehicles where intended to carry but one

person, and upon each seat-arm *d* may be supported an individual foot-rest or stirrup, *l*, placed at a convenient distance from the seat. These rests or stirrups *l* may be of any suitable shape, and of wood, iron, or other suitable material. In the form shown they are secured beneath the seat-arms *d* by clips *m* and by braces *n*. They may be attached, however, by any suitable device or fastening, and they may 70 be secured and given position on any part of the seat-arms *d*, either upon the top or sides of them. This form affords foot-rests or stirrups which rise and fall with the seat, and being placed at the sides of the vehicle, or nearly so, 75 out of the way of the action of the horse, they have an advantage over other kinds of foot-supports for track or speed purposes, where it is desirable and necessary to hitch the horse 80 as near the axle as possible. 85

The whiffletree *j* is secured beneath the cross-bar *k* in the ordinary manner, and it is made of wood or other suitable material, so bent, shaped, or formed that the ends thereof to which the traces of the harness are attached 90 are thrown forward out from under the cross-bar, where its ends can be readily seen and the traces more easily attached than when covered by the cross-bar. And there is this further advantage in my form of whiffletree: The 95 shafts of the vehicle being longer than those in use in most other vehicles, by throwing the ends of the whiffletree forward, as shown and described, I am enabled to use a harness that has been previously adjusted for the shorter 100 shafts of other vehicles without the labor of letting out or lengthening its traces, while I keep the cross-bar back where it cannot interfere with the action of the horse when driven at speed. 105

What I claim as new, and desire to secure by Letters Patent, is—

1. The combination, with the shafts of a sulky, of the seat-arms, adjustably connected thereto and movable longitudinally thereupon, 110 substantially as described, and for the purpose set forth.

2. The combination, with the sulky-shafts, of the plates having loops or pivot-holes formed therein, and the seat-arms and foot-support 115 pivoted to said plate, said foot-support being at its rear end suspended from said seat-arms, substantially as described.

3. The combination, with a sulky-frame, of the suitably-supported longitudinally-adjusted 120 seat-supporting arms and the adjustable seat supported by said arms, substantially as described.

4. The combination, with the sulky-shafts and the rearwardly-extending seat-supporting 125 arms secured thereto, of the adjustable seat supported by said arms, substantially as described.

5. The combination, with the shafts *c*, connected by the cross-bar *k*, which has the whiffletree *j* attached thereto, of the suspended 130 foot-support composed of a suitable slat-sup-

porting frame and the rearwardly-curved slats *h*, the side bars of the foot-support being attached to the shafts in advance of the whiffletree, substantially as described, whereby a convenient foot-support below the shafts and on each side of the horse may be obtained.

6. The foot-support composed of a suitable slat-supporting frame and the rearwardly-curved slats *h*, having their ends secured to said frame, substantially as and for the purpose set forth.

7. The combination, with the shafts *c*, cross-bar *k*, and seat-arms *d*, pivoted to said shafts, of the springs *i*, arranged upon said cross-bar and under said seat-arms, substantially as described. 15

JAMES H. BLACKMORE.

In presence of—

FRANK M. NOBLES,
H. E. KILBOURNE.
